SLIDING AND SWINGING WINDOW
STRUCTURE

Arthur Douglas Utley, deceased, late of Liverpool,
England, by Thomas Utley, administrator,
Liverpool, England, and Almond Tinkler, Liver-
pool, England

Application March 29, 1949, Serial No. 84,164

Claims priority, application Great Britain
March 30, 1948

7 Claims. (Cl. 20—42)

1

This invention relates to sliding windows, and has for its object to provide a sliding window assemblage, more particularly, but of course, not exclusively, for use on shipboard, the window whereof may be readily raised or lowered by means of hand pressure alone, is automatically rendered watertight after movement without the aid of extraneous hand screws, or the like, and which, being of simple and robust construction, is relatively cheap to produce.

According to our invention, a sliding window assemblage comprises a frame adapted for fitting to a window aperture, and a counterbalanced sheet of glass or other appropriate material (hereinafter, for convenience of reference only, designated "glass") associated with said frame and adapted to be raised or lowered by hand into and out of aperture-closing position, and said assemblage being characterised in that the combined weight of said glass and the means whereby it is counterbalanced is utilized to effect, automatically, the watertight seating or sealing and locking of said glass (after movement thereof) against the adjacent frame or frame portion. Our invention is further characterised in that seating or sealing and locking of said glass may be effected in any position of vertical adjustment in which the glass may be placed.

In one embodiment, our invention comprises a frame to each side whereof is pivotally secured, by means of two or more parallel links or shackles, a vertical housing; a pair of rack bars slidably located in each housing and in opposed engagement with a pinion positioned therebetween and rotatably journaled in said housing; and a sheet of glass secured adjacent its edges to a rack bar of each housing, the co-operating rack bars being provided with individual balance weights, or alternatively a single weight common to both.

One or more of the links or shackles is or are provided with a toothed quadrant in engagement with a hand-operable pinion, whereby the glass and counterbalancing mechanism is pivoted about said shackles away from the frame to permit ready adjustment of said window by hand.

We will further describe our invention with the aid of the accompanying sheets of explanatory drawings which illustrate, by way of example only, and not of limitation, one mode of embodying same.

In said drawings, in which like characters of reference denote like parts wherever they occur,

Fig. 1 is a front elevation of a window assemblage suitable for use on shipboard,

Fig. 2 is a side elevation,

2

Fig. 3 is a section drawn to an enlarged scale as compared with the preceding views, taken as on line A—A, Fig. 1.

Fig. 4 is a section of a rack bar housing, taken as on line B—B, Fig. 2, and drawn to an enlarged scale as compared with Fig. 3; and

Fig. 5 is a fragmentary elevation in part section.

Referring now to said drawings, 1 denotes a metal frame with securing bolt holes 2 and a spigot portion 3 adapted to enter the window aperture of a ship's plating. Pivoted at each side of frame 1 on pins 4, 4 are two connecting links 5, 5^x which carry at their outer ends, by means of cranked pins 6, 6, a vertical housing 7; said cranked pins 6, 6 permit adjustment of the effective length of links 5, 5^x. Pins 6 are adjustably located at one end within bifurcated end portions 5^a of links 5, 5^x by means of screws 5^b, and are provided with medial flats 6^a whereby they may be turned to required positions of adjustment with the aid of an appropriate spanner. Links 5, 5^x are therefore capable of being readily adjusted to permit the fitting of glass, and/or resilient seating therefore, of various thicknesses. The other ends of said pins 6 are revolubly located in apertures provided for their reception in housing 7, and thus said housing 7 is permitted a limited amount of arcuate movement at the end of links 5, 5^x, and consequently toward, or away from frame 1, while maintaining its parallel relationship therewith.

Slidably located within each housing 7 are a pair of rack-bars 9, 10 in opposed engagement with a pinion 11 free to rotate about a spindle 12 on ball races 13, 13. Said spindle 12 is secured within housing 7 by means of an enlarged head portion 12^a and a screw 12^b. A sheet of glass 14, provided with a handle 15, is secured in any convenient manner to rack bars 9, 9, and a weight 8 is bolted to the lower extremities of co-operating rack bars 10, 10 in order to counterbalance the weight of rack bars 9, 9 and attached glass 14. The rack-bar housings 7 and the pinions 11 are preferably formed of Bakalised linen, or synthetic resin board, in order that the movement may be self-lubricating.

The two lower links 5^x, 5^x are each provided with a toothed quadrant 5^c, and in operative engagement with said quadrants are pinions 16, 16, keyed to a shaft 17 journaled in side brackets 18^a, 18^b of frame 1. The length of shaft 17 may be adjusted by means of a pin-and-sleeve joint 18.

One end 17^a of shaft 17 is entered into a gear

box 19 secured to a bracket extension 1b of frame 1, and secured thereto is a bevel wheel 20 arranged to mesh with a pinion 21 secured to a spindle 22 which, being disposed at right angles to shaft 17, is journalled at each end in bushings 19a screwed into the sides of gear box 19. An end 22a of spindle 22 projects exteriorly of gear box 19 and is adapted to be engaged by a handle 23 whereby pinion 21, bevel wheel 20, and so shaft 17 is rotated. Other types of gearing may, of course, be utilized in place of that described, and may be disposed on either side of frame 1 as desired: in some instances gearing may be omitted and suitable toggle or other linkage substituted therefor, or, handle 23 may be secured directly to shaft 17.

Normally, the combined weight of the counterbalanced assembly carried at the ends of links 5, 5x, 5, 5x, causes glass 14 to bear against a sealing strip 24 of rubber, or other suitable resilient material, which is fitted around the window aperture of frame 1, and, when the glass is in a lowered position, against vertical rubber seating strips 25 secured to frame 1 below the window aperture. Thus, an all round watertight joint is attained between glass and frame when the window is closed i. e. when glass 14 is in its uppermost position; and when said glass is partially or fully lowered, a watertight joint is still maintained between said glass and the adjacent portions of sealing strip 24.

The abutment of glass 14 against strips 24 and 25 effectively prevents the raising or lowering of said glass until the assembly carried by links 5, 5x, 5, 5x is pivoted upward and so away from frame 1. This latter operation is achieved by turning the handle 23 (as indicated by arrow in Fig. 1) when pinions 16 on shaft 17 are rotated to move toothed quadrants 5c, 5c of links 5x, 5x upward. Housings 7, 7 are thus pivoted upwards and glass 14 moves clear of sealing strips 24 and 25, and while in this latter state the position of glass 14 in relation to the window aperture may be readily changed by appropriate finger-tip pressure on handle 15.

When frame 1 is fitted to a ship's plating—being secured thereto in watertight manner by bolts passed through apertures 2—the weight of housings 7, 7, and associated parts being supported by links 5, 5x, 5, 5x, causes the glass 14 (assuming it to be in its uppermost position) to press firmly against the rubber sealing strip 24, thus forming a watertight joint and effectively sealing the window aperture, and automatically locking the glass in position. If it is desired to open the window, handle 23 is turned, thus rotating—through pinion 21 bevel wheel 20 and shaft 17—the two co-acting pinions 18, which co-operate with quadrants 5c of links 5x to move glass 14 out of sealing abutment with strip 24. It is to be noted that when released handle 23 will automatically return to its original position, and—by reason of the weight of housings 7 and associated parts acting on quadrants 5c and so pinions 16—the glass 14 is locked in its new 65 position.

To limit the upward travel of glass 14 a rubber or other stop 26 is secured adjacent to the top of frame 1 as illustrated, and to limit upward movement of weight 8 and so downward movement of glass 14, a rubber stop 27 is provided on the upper edge of the weight 8. Strips 25 positioned on either side of frame 1 ensure a parallel seating for glass 14 when it is in other than aperture closing position.

With the object of preventing water passing between housing 7 and the adjacent sides of frame 1 when the window is partially or fully opened, angle strips 28 are secured—as by screws 5 29—around the perimeter of frame 1, and which strips are adapted to guide water seepage, into a conventional drip tray (not shown) fitted below the window and so outboard of the ship.

As said hand-lever is positioned on the inside 10 of the window, unauthorized opening of same from the outside cannot be effected.

In an alternative method of securing the window assembly to the main frame, the pivotal shackles may be replaced by upwardly inclined 15 and slotted members immovably secured to said main frame. Appropriately spaced pins fitted on either side of the rack and pinion housings are entered in said slots, and the inclinations thereof and the weight of the window and control mechanism effect the required water-tightness of the 20 window.

The clearance necessary to raise or lower the window may be obtained in this instance, say, by 25 lever-actuated cams adapted to urge the assembly upward, and therefore away, from the sealing material.

In a further embodiment, the rack and pinion 30 gearing may be replaced by double-cut right and left hand screw-threaded rods of coarse pitch which cause a balancing weight or weights associated with nuts working on said rod to be moved in a direction opposite to that of the window as the latter is raised or lowered.

It will be apparent that windows constructed 35 according to our invention may be utilized with advantage in all circumstances where sliding windows are required, and that the construction and arrangement of component parts may be varied without departing from the scope of the 40 invention.

What we claim as our invention, and desire 45 to secure by Letters Patent is:

1. Counterbalance and operating means for a 50 spaced vertical housings, parallel links for securing said housings to a window frame, a pair of rack bars slidably located in each of said housings, a pinion positioned between each pair of rack bars in opposed engagement therewith and rotatably journalled in said housing, a transparent sheet for closing the window-aperture being secured to one of the rack-bars of each housing, and counter balancing weights secured to 55 said co-operating rack bars.

2. Counterbalance and operating means for a 60 spaced vertical housings positioned one at each side of a window frame, two pairs of parallel links for securing said housings to said frame, a pair of rack bars slidably located in each of said housings, a pinion positioned between each pair of rack bars in opposed engagement therewith and rotatably journalled in said housings, a transparent sheet secured to a rack bar of each housing, counterbalancing weights secured to the cooperating rack bars, toothed quadrants provided on one pair of said parallel links, and a shaft rotatably secured transversely of said frame, pinions keyed to said shaft being in engagement with said quadrants for moving said counterbalancing mechanism and transparent sheet clear of said frame.

3. Counterbalance and operating means for a 70 sliding and swinging window comprising two vertical housings positioned one at each side of a

window frame, two pairs of parallel links pivoted to said housings for securing it to said frame, a pair of rack bars slidably located in each of said housings, a pinion positioned between each pair of rack bars in opposed engagement therewith and rotatably journaled in said housings, a transparent sheet for closing the window aperture being secured to a rack bar of each housing, a counterbalancing weight secured to the other co-operating rack bar, toothed quadrants provided on the lower pair of said parallel links, pinions in engagement with said quadrants, a shaft rotatably secured transversely of said frame having said pinions keyed thereto for moving said sheet and its counterbalancing mechanism clear of said frame, and a handle situated at a side of said frame for rotating said transverse shaft through bevel gears.

4. Counterbalance and operating means for a sliding and swinging window as claimed in claim 3 wherein said rack bar housings are pivotally secured to said parallel links by means of cranked pins whereby the effective length of said links may be altered.

5. Counterbalance and operating means for a sliding and swinging window comprising two vertical housings positioned one at each side of a window frame, two pairs of parallel links for securing said housings to said frame, cranked pins pivotally securing said housings to said links, a pair of rack bars slidably located in each of said housings, a pinion positioned between each pair of rack bars in opposed engagement therewith and rotatably journaled in said housing, a transparent sheet for closing the window aperture being secured to a rack bar of each housing, counterbalance weights secured to the co-operating rack bars, toothed quadrants provided on the lower pair of said parallel links, pinions in engagement with said quadrants, a shaft rotatably secured transversely of the said frame for moving said sheet and its counterbalancing mechanism clear of said frame and having said pinions keyed thereto, a handle situated at a side of said frame for rotating said shaft through bevel gears, a sealing strip of resilient material provided around the window aperture of said frame, and side strips of similar material being provided below said window aperture to ensure correct seating of said transparent sheet when in its lowered position.

6. Counterbalance and operating means for a

sliding and swinging window comprising two vertical housings positioned one at each side of a window frame, parallel and pivotal links for securing said housings to said frame, a pair of rack bars slidably located in each of said housings, a pinion positioned between each pair of said rack bars in opposed engagement therewith and rotatably journaled in said housings, a sheet of glass secured to one of the rack bars in each housing, a counterbalance weight secured to the co-operating rack bars, toothed quadrants provided on a pair of said pivotal links, pinions in engagement with said quadrants, a shaft keyed to said pinions and rotatably secured to said frame for being rotated by hand to move the glass from watertight seating and locking abutment with said frame, and a handle attached to the upper portion of said glass sheet whereby said glass is moved to any desired position of vertical adjustment.

7. A sliding and swinging window assembly comprising a frame for being mounted in a window aperture, two vertical housings positioned one at each side of said frame, two pairs of rack bars each slidably located in one of said housings, a pinion positioned between each pair of said rack bars in opposed engagement therewith and rotatably journaled in said housing, a transparent sheet for closing the window aperture secured to one of the rack bars of each of said housings, a counterbalancing weight connected to said co-operating rack bars, and parallel links connecting said rack bar housings to said frame whereby the combined weight of said sheet and its supporting and counterbalancing means operates automatically to lock and give a watertight sealing of said sheet against said frame in any position of adjustment.
